UNITED STATES PATENT OFFICE.

EDMUND E. EGGLESTON, OF WICHITA, KANSAS.

BICYCLE-LOCK.

979,453.

Specification of Letters Patent. Patented Dec. 27, 1910.

Application filed February 5, 1910. Serial No. 542,258.

To all whom it may concern:

Be it known that I, EDMUND E. EGGLESTON, a citizen of the United States, residing at Wichita, in the county of Sedgwick and State of Kansas, have invented certain new and useful Improvements in Bicycle-Locks, of which the following is a specification.

My invention relates to an improvement 10 in bicycle locks, and the object is to provide a device which may be applied to one of the standards of the machine at a point where it is out of the way, and at the same time 15 may be conveniently brought into play to lock the wheel when desired without the use of a key, and which will require a key especially provided for it to unlock the machine.

A further object is to provide a lock which cannot be easily taken apart or picked.

With these objects in view, my invention 20 consists in a locking member having a bolt attached thereto, the locking member inclosing the locking mechanism, and a lock case made in two sections and secured to the 25 frame of the machine, and the bolt adapted to be swung between the spokes of the wheel, whereupon the locking mechanism automatically secures the bolt in place until the key 30 designed to unlock it is used in the lock.

My invention further consists in certain 35 novel features of construction and combinations of parts which will be hereinafter described and pointed out in the claims.

In the accompanying drawings:—Figure 35 1 shows a portion of a bicycle with my improved lock in position on the right rear standard; Fig. 2 shows the internal construction of the lock, the top portion of the case being removed; Fig. 3 is a side elevation looking from beneath; Fig. 4 is a perspective view of the top half of the lock 40 case; Fig. 5 is a similar view of the lower half or section of the same; and Fig. 6 is an illustration of one of the screws, preferably 45 used to secure the two halves of the lock case together.

This lock is adapted to be permanently attached to the frame of the bicycle, and when the bolt is in the position shown in Fig. 1, 50 the wheel is unlocked. This bolt 1 is attached to member 2, which latter member rotates within the casing of the lock. The casing is made of two parts, as illustrated in Figs. 4 and 5. Within the member are 55 the pawls 3 and 4. One end of each pawl is designed to enter notches contained in mem-

ber 2. These pawls are forced into the notches by springs 5 and 6. These pawls 3 and 4 have projections 7 and 8 respectively with which the wings of the key 9 engage 60 to force the pawls out of the notches, thus leaving member 2 free to rotate.

To lock a bicycle, the member or bolt 1 is turned so as to extend between the spokes of the wheel 10. The pawls 3 and 4 now 65 engage the notches where they remain until the key 9 is inserted and rotated. It will be noted that member 2 contains a double set of notches. This is to lock the bolt out of the wheel as well as in the wheel, to avoid 70 accident while running on the road. It will be seen that one side of each of the notches used to lock the bolt out of the wheel is beveled so that the proper amount of force will 75 force the bolt between the wheel spokes without using the key, thus saving time.

The lock is put on the wheel frame as follows: The countersunk screws 11 and 12 are passed through holes in the lower case 80 member and screwed into clamp 13. The top portion of the case is now put in position, and screws having, in addition to a countersunk head, a square projection, are passed through top portion of case and 85 screwed in lower portion. The square projection is now cut away, leaving the top of case smooth. This method of attaching makes it very difficult to remove the lock from the bicycle frame.

It is evident that more or less slight 90 changes might be resorted to in the form and arrangement of the several parts described, without departing from the spirit and scope of my invention, and hence, I do not wish to limit myself to the exact construction herein set forth, but:—

Having fully described my invention, what I claim as new and desire to secure by Letters Patent, is:—

1. A lock comprising a case made in sections, spring-actuated pawls pivotally connected thereto, a bolt, and a locking member connected to the bolt and rotatably supported within the case and provided with two varieties of internal notches adapted to 105 be automatically engaged by the pawls, one variety of notches being adapted to co-act with the pawls to lock the bolt in position, and the other variety of notches being constructed each with an inclined wall, whereby 110 said notches are engaged by the pawls, the bolt will be yieldingly held in position.

2. A lock comprising a case having an upper and lower section, a clamp connected to the lower section, means connecting the two sections together, spring-actuated pawls ⁵ pivotally mounted within the case, a bolt, and a locking member connected to the bolt, and rotatably supported within the case and provided with two varieties of internal notches adapted to be automatically engaged ¹⁰ by the pawls, one variety of notches being adapted to co-act with the pawls to lock the

bolt in position, and the other variety of notches being constructed with an inclined wall, whereby when said notches are engaged by the pawls, the bolt will be yieldingly held in position. ¹⁵

In testimony whereof I affix my signature, in the presence of two witnesses.

EDMUND E. EGGLESTON.
